MOVEABLE SIGNAL LIGHT FOR STORE SALES

Robert M. Akers, Oklahoma City, Okla., assignor of a
fractional part interest to Thomas Pickering

Filed Sept. 10, 1970, Ser. No. 24,924

Term of patent 14 years

Int. Cl. D31

U.S. Cl. D72—1

FIG. 1 is a front elevational view of a moveable signal light for store sales showing my new design;

FIG. 2 is a side elevational view thereof;

FIG. 3 is a top plan view thereof;

FIG. 4 is an elevational view of the side opposite that shown in FIG. 2;

FIG. 5 is a rear elevational view thereof;

FIG. 6 is a bottom plan view thereof.

I claim:

The ornamental design for a moveable signal light for store sales, as shown.
